attorney.

UNITED STATES PATENT OFFICE.

JOHN G. HOMAN, OF STEUBENVILLE, OHIO, ASSIGNEE TO ELECTROTHERMAL COMPANY, OF STEUBENVILLE, OHIO, A FIRM COMPOSED OF SAID JOHN G. HOMAN, OF STEUBENVILLE, OHIO, AND WILLIAM J. KIRK, OF FOLLANSBEE, WEST VIRGINIA.

DILATOR.

1,381,194.

Specification of Letters Patent. Patented June 14, 1921.

Application filed January 17, 1920. Serial No. 352,058.

To all whom it may concern:

Be it known that I, JOHN G. HOMAN, a citizen of the United States, and a resident of Steubenville, in the county of Jefferson and State of Ohio, have invented a new and useful Improvement in Dilators; and I do hereby declare the following to be a full, clear, and exact description thereof.

My invention relates to dilators, and has special reference to electrically heated dilators, such as is shown, described and claimed in United States Letters Patent No. 1,279,111 granted to me on September 17, 1918.

The object of my invention is to provide a cheap, simple and efficient dilator in which the electric heat giving element will be associated with an electric light giving construction, and thereby produce a stimulation deeper into the tissues of rectal anatomy than would be possible with mere heat alone.

To these ends my invention consists, generally stated, in the novel arrangement, construction and combination of parts, as hereinafter more specifically set forth and described and particularly pointed out in the claims.

To enable others skilled in the art to which my invention appertains to construct and use my improved dilator, I will describe the same more fully, referring to the accompanying drawing, in which:

Figure 1 is a longitudinal section of a dilator employing my invention;

Fig. 2 is a similar section of the same, with the electric connector applied thereto for use with the lighting element only;

Fig. 3 is a like view showing the connector applied for use with the heating element only;

Fig. 4 shows the same view with the connector applied for using both the lighting and heating elements; and

Fig. 5 is a diagram view showing the wiring employed.

Like symbols of reference herein indicate like parts in each of the figures of the drawings.

As illustrated in the drawings, A represents my improved dilator which is provided with the body 1 having flanges 2 and 3 adjacent its rear end and an oval or egg-

shaped head portion 4 at its opposite end. This body 1 is formed of transparent material, such as glass, quartz or other such material, that will not deteriorate in any manner when sterilized, and is provided with a chamber or recess 5 formed within the same for the reception of the combined heat and light giving device 6, hereinafter described. This heating and lighting device may be of any desired form, and as shown consists of the heating element 7 and the light giving element 8, which device is carried by a plug or mounting member 9 adapted to be screwed or otherwise secured into the rear end of the body 1, and formed of an insulating material. The heating element 7 is formed of a resistor, such as a wire of resistance material, which is connected at one end by a wire 10 with a wire 11 connected to a wire 10, connected to the terminal 12 in the plug 9, and the other end of such resistor is connected to a wire 12, which is connected at its rear end to a terminal 12' in the plug 9. The lighting element is formed of a suitable wire filament, such as at 13, which is connected at one end to the connection between the resistor 7 and the wire 12^a and its opposite end to the connection between a wire 14, which is connected at its rear end with a terminal 12'' in the plug 9.

The terminals 12, 12' and 12'' extend beyond the rear face of the plug 9 and are adapted to fit within the usual recess or sockets 15 of a connector 16, which carries three cords or wire connectors suitably positioned therein, so that when such connector engages the plug 9, one conductor 17 will be connected to the terminal 12, one conductor 17' will be connected to the terminal 12' and the other connector 17'' will be connected to the terminal 12''.

When it is desired to use only the lighting element 8 in the dilator A, as shown in Fig. 2, the conductors 17' and 17'' in the connector 16 are connected to the terminals 12' and 12'', respectively, which will allow the current to pass through the wires 12^a and 14 and filament 13, and thereby allow the rays of visible light from such filament to pass or penetrate through the transparent head 4 in such dilator.

When it is desired to use only the heating element 7, in the dilator A, as shown in Fig. 3, the conductors 17 and 17' in the connector 16 are connected to the terminals 12 and 12', respectively, which will allow the current to pass through the wires 11, 10 and 12^a to the resistor 7, and thereby allow the heat from such resistor through the head 4 in the dilators.

10 When it is desired to use both the light giving element 8 and the heating element 7, as shown in Fig. 4, the conductors 17, 17' and 17'' in the connector 16 are connected to the terminals 12, 12' and 12'', respectively, which will allow the current to pass through the wires 11 and 10 from the terminals 17 and wire 12^a from the terminals 12' to the resistor 7, and through the wires 12' and 14 from the terminals 12' and 12'' to the filament 13, thereby allowing the heat from such resistor and the rays of visible light from such filament to pass through the transparent head 4 in the dilator.

It will be obvious to anyone skilled in the art that the light-giving, or heat-giving, or both elements 7 and 8 may be inclosed in a separate casing of glass or other material, as is customary in incandescent lamp making, such as is shown at 18, and if desired only 30 the portions of said casing and body 1 and adjacent the said elements need be transparent.

It will also be obvious that my improved dilator may be operated from a very low current, as a very small amount of energy is used, but in case it is desired to attach a higher current, a suitable resistance may be used to control the current, and placed within or without the dilator, as desired.

40 Various other modifications and changes in the construction and operation of my improved dilator, may be resorted to, without departing from the spirit of the invention or sacrificing any of its advantages.

45 It will thus be seen that the dilator can be used for various purposes and various parts of the body, with substantially the same effect being obtained, and will present a compact and beneficial device for dilating the muscles and at the same time excite the 50 nerves and gently stimulate the capillary blood vessels.

It will also be seen that the use of my dilator will furnish a constant heat with 55 safety to the anatomy and the reflex nerve action also has the effect of stimulating through the so-called abdominal brain, and other nerve centers, which centers will have the tendency to bring about normal healthy 60 conditions, and thus relieve an aggravating cause of a number of diseases, while the heat being produced by a very low voltage, without cumbersome design, danger from shock is entirely eliminated, and in most cases one 65 volt is sufficient to produce the desired heat.

The heating and lighting element being removable from the casing will enable repairs and renewals of parts when desired.

What I claim as my invention and desire to secure by Letters Patent is:

70

1. A dilator comprising a hollow casing having a transparent portion, means therein for emitting light, other means therein for emitting heat, and separate controlling means including separate circuits for each 75 of said means.

2. A dilator comprising a hollow casing having a transparent portion, means therein for emitting light, other separate means therein for emitting heat, and selective 80 means, including separate circuits, for rendering either or both of said light and heat emitting means effective.

3. A dilator comprising a base having a threaded side portion, conductors passing through said base, a filament comprising a heating section and a lighting section connected to the conductors, a casing surrounding such filament, and a second casing 85 forming the dilator, said casing being screwed to the threaded portion of the base, and means whereby either or both of said filament sections may be rendered effective.

4. A dilator comprising a hollow casing having a filament composed of two different 95 sections, one of said sections being essentially a light emitting section and the other section being essentially a heat emitting section, and means including separate circuits for connecting the filaments to a source of 100 current.

5. A dilator comprising a hollow casing having a filament composed of two different sections, one of said sections being essentially a light emitting section and the other section being essentially a heat emitting section and means at one end of the casing 105 for selectively connecting the filament sections to a source of current whereby either or both may be rendered effective.

110

6. A dilator comprising a casing having a chamber therein, said casing having a transparent portion, an electric light giving element within said chamber, an independent electric heating element within said chamber, said elements being adapted to emit radiations of visible light or heat or both through said transparent portion, and means associated with either or both of said elements for connecting the same with a 120 source of current.

115

7. A dilator comprising a casing having a chamber therein, said casing having a transparent portion, an electric light giving element within said chamber, an independent electric heating element within said chamber, said elements being adapted to emit radiations of visible light or heat or both through said transparent portion, a 125 mounting member of insulating material se- 130

cured within said casing terminals within said member for carrying said elements, and means associated with said terminals for connecting either or both of said elements 5 with a source of current.

8. A dilator comprising a casing having a chamber therein, said casing having a transparent portion, an electric light giving element within said chamber and comprising 10 a filament having wires connected thereto, an independent electric heating element within said chamber comprising a resistance member having wires connected thereto, said elements being adapted to emit radi-

ations of visible light or heat or both 15 through said transparent portion, a mounting member of insulating material secured within said casing, terminals within said member and connected to said wires, and means associated with said terminals for 20 connecting either or both of said elements with a source of current.

In testimony whereof, I, the said JOHN G. HOMAN, have hereunto set my hand.

JOHN G. HOMAN.

Witness:

J. N. COOKE.
